CLAIM

We claim the ornamental design for an electronic device, as shown and described.

DESCRIPTION

FIG. 1 is a rear perspective view of an electronic device showing our new design;

FIG. 2 is a rear view thereof;

FIG. 3 is a front view thereof;

FIG. 4 is a left-side view thereof;

FIG. 5 is a right-side view thereof;

FIG. 6 is a top view thereof; and,

FIG. 7 is a bottom view thereof.

(Continued)

The broken lines in the figures depict portions of the electronic device which form no part of the claimed design.

1 Claim, 7 Drawing Sheets
